EXTENSION TABLE

Cecil D. Lamum, Bloomington, Ind.

Application March 16, 1935, Serial No. 11,506

1 Claim. (Cl. 311—55)

This invention relates to new and useful improvements in extension tables, and has for its primary object to provide a more satisfactory method of extending and supporting the leaves of a table of the "draw end" type, than any now in use.

In carrying out my invention, I provide two corresponding pairs of slides and mount two metal dowels in each slide in such a manner that one acts as a stop and the other supports the leaf upon the end rail of the table when in open or extended position. I also provide guiding means at the center of the table for both pairs of slides and means for adjusting or elevating the end leaves to insure a perfect fit between the co-acting lips at the outer edges of the stationary center leaf or section and the inner edges of the end leaves. Means are also provided at the inner ends of the slides to elevate the end leaves level with the center of the table when the former are opened or extended.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a bottom plan view of an end extension table, embodying my improvements.

Figure 2 is an end view, the legs partly broken away.

Figure 3 is a side elevation.

Figure 4 is a vertical longitudinal section, taken on line 4—4 of Figure 1.

Figure 5 is a similar view, with one end leaf extended and the other end of the table broken away.

Figure 6 is a vertical transverse section, taken on line 6—6 of Figure 4.

Figure 7 is a detail horizontal fragmentary section, taken on line 7—7 of Figure 6.

Figure 8 is a vertical transverse section, taken on line 8—8 of Figure 5.

Figure 9 is a similar view, taken on line 9—9 of Figure 8 and Figure 10 is an enlarged detail fragmentary sectional view.

Referring to the drawings for a more particular description of my invention, and in which drawings like parts are designated by like reference characters throughout the several views, the numeral 1 designates the side rails, 2 the end rails,

3 the supporting legs, 4 the stationary center leaf or section and 5 and 6 the corresponding end leaves.

In carrying out my invention, I provide the end leaf 5 with two corresponding parallel slides 7, which are disposed longitudinally of the table top and situated at opposite sides thereof, within the space between the side rails 1. The end leaf 6 is also provided with two corresponding longitudinally disposed slides 8, which are also disposed at opposite sides of the table top, between and in parallel relation with the slides 7. The slides 7 and 8 are suitably attached at their outer ends and upper edges, as at 9, to the bottom faces of the end leaves 5 and 6, respectively, and each slide is provided with a transverse horizontally disposed metal dowel pin 10, which is located at the free end of the slide and acts as a stop in limiting the outward movement of the corresponding end leaf and is further provided with a second transverse horizontally disposed metal dowel pin 11, which is located adjacent the center of the slide and serves to support the corresponding end leaf on the adjacent end rail when open or extended. The slides 7 and 8 pass through transverse recesses 12 formed in the upper edge of the central transverse guide bar or member 13 and work against the opposite sides of the central vertically disposed dowel pins 14, carried by said guide bar and extending into said recesses.

The end rails 2 are formed in their upper edges with transverse recesses 15 to receive the outer ends of the slides 7 and 8, and said recesses 15 are formed in turn with lateral extensions 16 to receive the outer projecting ends 16' of the dowel pins 11. Said end rails are also formed in their upper edges with longitudinal grooves 17 in which the projecting ends of the dowel pins 11 rest when the end leaves are in open or extended position, as will more fully hereinafter appear. The inner or free ends of the slides 7 and 8 are provided on their bottom edges with elongated blocks or shoes 18 and 19, respectively, formed with beveled inner edges 20 and 21. When the end leaves are opened or extended, as illustrated in Figure 5 of the drawings, the blocks or shoes 18 and 19 rest on the upper edge of the central guide bar or member 13 and raise or elevate the leaves on a level with the stationary center leaf or section 4.

Set screws 22 are mounted in corresponding vertical openings 23, in the upper edges of the end rails 2, directly beneath the projecting ends of the dowel pins 11, and facilitate the adjustment of the end leaves in perfect horizontal alinement,

with the ends of the center leaf or section 4. The set screws 22 are formed with hollow hexagonal heads 24 and the bottom edges of the end rails 2 formed with vertical bores or openings 25 to facilitate the introduction and use of a hexagonal wrench (not shown) in adjusting said set screws.

In practice, the end leaves 5 and 6 are arranged in normal position ready for use, by first withdrawing the same from retracted or closed position, as illustrated in Figure 4 of the drawings, until the projecting ends 16' of the dowel pins 11 extend entirely through the lateral extensions or recesses 16 of the openings 15 in the end rails 2, after which operation, the end leaves 5 are raised and pushed back until the lips 26 formed at the upper inner edges thereof interlock with the lips 21 of the center leaf or section 4, and the projecting ends 16' of the dowel pins 11 rest in the grooves 17 in the upper edges of the end rails. The end leaves are thus supported on the end rails of the table and the inner ends of the slides 7 and 8 on the central guide bar or member 13 by the beveled blocks or shoes 18 and 19. Should any adjustment of the end leaves be required to bring their inner edges into perfect horizontal alinement with the outer edges of the stationary center leaf or section, this may be accomplished by adjusting the set screws 22 by means of a suitable wrench.

From the foregoing description taken in connection with the drawings, it is thought that the construction, operation and advantages of my invention will be readily understood without requiring a more extended explanation.

Having described my invention, what I claim as new and desire to secure by Letters Patent, is:

In an extension table of the character specified, a top comprising side and end rails, a stationary center leaf and adjustable end leaves, said end rails formed with transverse openings having lateral extensions and with grooved upper edges, a pair of slides carried by each end leaf and working through the transverse openings in the end rails, guiding means for the slides, means to limit the outward movement of the slides, horizontal dowel pins carried by the slides and adapted to rest in the grooved upper edges of the end rails when the end leaves are in open or extended position, bevel blocks carried by the free ends of the slides and co-operating with the dowel pins in supporting said end leaves on a level with the center leaf and set screws mounted in the upper edges of the end rails directly beneath the projecting ends of the dowel pins when in groove engaging position, for adjusting the end leaves in perfect horizontal alinement with the ends of the stationary center leaf.

CECIL D. LANUM.
